UNITED STATES PATENT OFFICE.

NATHANIEL L. RIPLEY, OF BOSTON, MASSACHUSETTS.

DESIGN FOR A JEWEL-SETTING.

SPECIFICATION forming part of Design No. 19,830, dated May 6, 1890.

Application filed March 12, 1890. Serial No. 343,666. Term of patent 3½ years.

To all whom it may concern:

Be it known that I, NATHANIEL L. RIPLEY, a citizen of the United States, residing at Boston, county of Suffolk, and State of Massachusetts, have invented and produced a new and original Design for a Jewel-Setting, of which the following is a specification, reference being had to the accompanying drawing, forming part thereof.

10 The drawing represents in side elevation a jewel-setting embodying this invention.

The leading feature of my design consists in a series of spear-points *a* arranged on a base or ring *a'*, the laterally-broadened portion between the point and the shank forming the spear-point. The shanks of the spear-points are split and turned in opposite directions, forming connections by which the adjacent spear-points are joined together. The

broadened part of the spear-points may also 20 be connected to one another.

The jewel-setting, or "skeleton frame," as it is oftentimes called, is used as an ear-drop, stud, ring, or other article of jewelry.

I claim—

25 The design for a jewel-setting herein shown and described, consisting of a series of spear-points arranged on a base, each having a laterally-broadened portion between its point and shank, substantially as described.

30 In testimony whereof I have signed my name to this specification in the presence of two subscribing witnesses.

NATHL. L. RIPLEY.
